CLAIM

The ornamental design for a pet feeder, as shown and described.

DESCRIPTION

FIG. 1 is a top perspective view of a pet feeder, showing my new design.

FIG. 2 is a front view of the pet feeder.

FIG. 3 is a rear view of the pet feeder.

FIG. 4 is a left view of the pet feeder.

FIG. 5 is a right view of the pet feeder.

FIG. 6 is a top view of the pet feeder.

FIG. 7 is a bottom view of the pet feeder.

FIG. 8 is an enlarged view of detail "8", identified in FIG. 4; and,

FIG. 9 is a bottom perspective view of the pet feeder.

The broken lines in FIGS. 4 and 8 depict the boundaries of the enlargements and form no part of the claimed design. The remaining broken lines in the drawings depict portions of the pet feeder that form no part of the claimed design.

1 Claim, 9 Drawing Sheets
